UNITED STATES PATENT OFFICE.

JOHN L. MOHUN, OF BROOKLYN, NEW YORK.

CAR-ROOF STRUCTURE.

1,119,305.

Specification of Letters Patent.

Patented Dec. 1, 1914.

Application filed January 25, 1913. Serial No. 744,075.

To all whom it may concern:

Be it known that I, JOHN L. MOHUN, a citizen of the United States, residing at Brooklyn, in the county of Kings and State of New York, have invented a certain new and useful Improvement in Car-Roof Structures, of which improvement the following is a specification.

This invention relates to car roof construction in which transverse metal roofing sheets are employed, having their adjacent side edges adapted to drain into a trough which discharges over the sides of the car, such as shown in my prior Patent No. 1,077,631, dated November 4, 1913, and one of the objects of my invention is to provide an improved joint construction between the roofing sheets and the drain trough at the end portions of the latter over the side plates 20 of the car, whereby the trough may be diminished in height to provide additional clearance at the eaves of the car.

Another object is to provide improved means for fastening the end of the cap over the discharge end of the trough at the side plate whereby the end of the cap is spaced from the side plate to provide ample clearance for the discharge of drain water from the trough.

In the accompanying drawing: Figure 1 is a transverse section of a portion of my improved car roof at the side plate of the car; Fig. 2, a side elevation of the same; the cap section and the roofing sheet at one side being removed to show the trough construction and the form of joint between the trough and the edge of the roofing sheet; Fig. 3, a plan of the same with the cap section in place; and Figs. 4, 5, and 6, transverse sections of the trough, roofing sheets and cap, taken on the lines 4—4, 5—5, and 6—6, respectively of Fig. 1.

As shown in the drawings, my improvement is applied in connection with that type of car roof in which a transverse drain trough, 12, is employed and the metal roofing sheets, 7, extend transversely across the car with their adjacent side edges located over said drain trough. The metal drain trough is preferably U shaped in cross section having vertical side walls and the lateral edges of the roofing sheets, 7, are turned up to form a vertical portion, 7^a, and a lateral flange, 7^b, extending over the top 55 of the trough to substantially the center line, as indicated in Figs. 2 and 3.

The ends of the drain trough over the side plates, 11, of the car are flared out at 12^a, and the side walls of the trough diminish in height as at 12^b, making the trough wider and more shallow at the point where it is turned down over the side plate, 11, which is preferably notched to form a recess for receiving the wider and shallower end portion, 12^a, of the trough. The shallow flanges, 12^b, of the trough may be turned out over the side face of the side plate, and the bottom of the trough is preferably extended at 12^c, upon the top surface of the facia, 16, which is secured to the side plate. 70

The metal roofing sheets, 7, preferably extend transversely from eaves to eaves of the car, and are provided with down-turned end flanges, 8, overhanging the sides of the car and spaced therefrom. For the purpose of 75 forming a close joint between the edges of the roofing sheets and the flared portion of the drain trough with diminishing flanges over the side plates, the lateral flanges, 7^b, of the edges of the roofing sheets are bent 80 downward as at 7^b, over the upper edge of the vertical side walls of the trough, as shown particularly in Figs. 4, 5, and 6. The up-turned portions, 7^a, of the edges of the roofing sheets are formed to follow the contour 85 of the flaring and diminishing side walls of the trough over the side plate and it will be apparent that any moisture that may be driven over the edges of the roofing sheets at this point will fall into the trough 90 and drain out over the side of the car.

The drain trough and the lateral edges of the roofing sheets are covered by a metal cap section, 13, which is preferably of an inverted U shaped section with broad lateral flanges resting upon the roofing sheets, and for the purpose of holding down the caps and roofing sheets, the caps are provided with down-turned end flanges, 14, 95 overhanging the sides of the car and secured to the side plates. My improved means for fastening the cap sections in position comprises a bridge piece, 17, spanning the discharge end of the trough and having lugs at its ends adapted to bear against the side 100 plate. The bridge piece is placed just beneath the end flange, 14, of the cap section, 13, and both are securely fastened in position by means of bolts, 18, extending through the cap flange and the bridge into 105 the side plates. The cap flanges is thus spaced from the side plate and ample clearance is 110.

afforded under the bridge piece for the discharge of water from the drain trough. The corner of the down-turned end flange, 8, of the roofing sheets may be cut out as indicated in Fig. 2, in order to clear the bridge piece, 17, at the point where the same is bolted to the side plate, thereby allowing for a slight relative movement between the roofing sheets and the side frame of the car.

10 It will now be apparent that by means of this improved construction, wherein the lateral drain troughs are provided with flaring end portions having their side walls diminishing in height over the side plates, 15 additional clearance is obtained at the eaves of the car without obstructing the flow or restricting the discharge capacity of the drain troughs.

Having now described my invention, what 20 I claim as new and desire to secure by Letters Patent is:

1. In a car roof, the combination of a transversely located metal drain trough having flaring end portions with diminishing 25 side walls extending down over the side of the side plates of the car, and metal roofing sheets extending transversely of the car and having their adjacent side edges located over said drain trough, the lateral edges of the 30 roofing sheets at the flared portion of the trough having flanges turned up and over said diminishing side walls.

2. In a car roof, the combination of a transversely located metal drain trough having flaring end portions with diminishing 35 side walls extending down over the side of the side plates of the car, and metal roofing sheets extending transversely of the car and having their adjacent side edges located over 40 said drain trough, the lateral edges of the roofing sheets at the flared portion of the trough having flanges turned up and over said diminishing side walls, and a metal cap covering said trough and having down 45 turned end flanges spaced from the side of the car.

3. In a car roof, the combination of a transversely located metal drain trough having flaring end portions with diminishing side walls extending down over the side of the side plates of the car, the side plates being notched to form a recess for the flared ends of said trough, and metal roofing sheets extending transversely of the car and having their adjacent side edges located over said drain trough, the lateral edges of the roofing sheets at the flared portion of the trough having flanges turned up and over said diminishing side walls.

4. In a car roof, the combination of a transversely located metal drain trough having flaring end portions with diminishing side walls extending over the side plates, metal roofing sheets extending transversely of the car with their adjacent side edges located over said trough and having end flanges extending down over the side plates of the car, the lateral edges of the roofing sheets having flanges turned up and over said diminishing side walls of the trough, 70 and a metal cap covering said trough and having down-turned end flanges spaced from the side plates of the car.

5. In a car roof, the combination of a transversely located metal drain trough having end portions extending over the side plates, metal roofing sheets extending transversely of the car with their adjacent side edges located over said trough and having end flanges extending down over the side 80 plates of the car, a metal cap covering said trough and having end flanges turned down over the side plates, bridge pieces spanning the ends of the trough beneath the cap flanges and having lugs bearing against the 85 side plates, and bolts for fastening the cap and said bridge pieces to the side plates.

JOHN L. MOHUN.
